(57) **CLAIM**

We claim the ornamental design for a battery operated toy coupe, as shown and described.

DESCRIPTION

FIG. 1 is a perspective view of a battery operated toy coupe embodying the invention.

FIG. 2 is a right side elevation view of the battery operated toy coupe shown in FIG. 1.

FIG. 3 is a left side elevation view of the battery operated toy coupe shown in FIG. 1.

FIG. 4 is a front elevation view of the battery operated toy coupe shown in FIG. 1.

FIG. 5 is a rear elevation view of the battery operated toy coupe shown in FIG. 1.

FIG. 6 is a top plan view of the battery operated toy coupe shown in FIG. 1; and,

FIG. 7 is a bottom plan view of the battery operated toy coupe shown in FIG. 1.

The broken lines showing the environment form no part of the claimed design.
